UNITED STATES PATENT OFFICE.

JOHN LOUCIEN CHESNUTT, OF KANSAS CITY, MISSOURI.

ELEVATING-TRUCK.

1,095,267.

Specification of Letters Patent.

Patented May 5, 1914.

Application filed July 18, 1913. Serial No. 730,091.

To all whom it may concern:

Be it known that I, JOHN L. CHESNUTT, a citizen of the United States of America, and resident of Kansas City, Jackson county, 5 Missouri, have invented a new and useful Elevating-Truck, of which the following is a specification.

The object of this invention is to provide an improved construction for an elevating 10 truck adapted to be moved beneath and raise a loaded platform.

A further object of this invention is to provide improved elevating devices in a lifting truck.

15 A further object of this invention is to provide improved latching devices in an elevating truck.

20 A further object of this invention is to provide improved means for tripping the latching devices.

25 My invention consists in the construction, arrangement and combination of elements hereinafter set forth, pointed out in my claims and illustrated by the accompanying drawing, in which—

Figure 1 is a plan of the lower frame. Fig. 2 is a plan of the complete truck in lowered position. Fig. 3 is a front elevation illustrating the device in position for 30 use beneath a platform. Fig. 4 is a longitudinal section on the line 4—4 of Fig. 2, showing the truck in elevated position. Figs. 5 and 6 are elevations on an enlarged scale of an inclined plane and roller employed in the lifting operation, said views 35 illustrating lowered and raised positions respectively.

In the construction of the device as shown a bottom frame is formed of side members 40 10, 11 and end members 12, 13, preferably of angle iron suitably joined at the corners. The side members 10, 11 preferably are arranged with their horizontal flanges extending inwardly from the bottoms of the vertical 45 flanges and resting on the horizontal flanges of the end members 12, 13, the vertical flanges of which extend downwardly from the outer margins of said horizontal flanges. The bottom frame also is formed 50 with cross-pieces 14, 15 near to but spaced from the end pieces 12, 13. The bottom frame is supported by rear casters or wheels 16 fixed beneath opposite ends of the members 13, 15, and by front or steering casters 55 17, 18 swiveled beneath opposite ends of the members 12, 14. Spaced arms 19, 20 are

fixed to the cross-piece 14 and front member 12, project forwardly beyond the latter member and a handle 21 is pivoted on a horizontal axis to and between said arms. A top frame is formed of side members 22, 23 and end members 24, 25, preferably of angle iron suitably joined at the corners. The side members 22, 23 preferably are arranged with their horizontal flanges extending outwardly 60 from the tops of the vertical flanges and forming box like spaces with the lower side members 10, 11 when the two frames are in juxtaposition. Oblique braces 26, 27 preferably are fixed to and connect the side members 22, 23 and front member 24 and rear portions of said braces are connected by cross members 28, 29. Brackets 30, 31, 32, 33 are formed on and rise from the horizontal flanges of the side members 10, 11 of the 65 bottom frame at the respective corners thereof, and with the vertical flanges of said members form channels or grooves in which rollers 34, 35, 36, 37 are mounted for rotation on pins 38, 39, 40, 41. Inclined planes 70 42, four in number, one of which is shown in Figs. 5 and 6, are fixed to lower faces of the side members 22, 23 of the upper frame at the respective corners thereof and said planes incline downwardly and rearwardly from 75 the horizontal flanges of said members. When the upper frame is in lowered position as illustrated in Fig. 2, said top frame projects to the rear of the lower frame and the inclined planes 42 rest at the rear of the respective rollers 34, 35, 36, 37, as shown in Fig. 5. When the upper frame is moved forwardly on the lower frame the inclined planes 42 rise on the respective rollers, as shown in Fig. 6 and elevate the upper frame 80 90 relative to the lower frame. An eye member 43 is fixed to and projects forwardly from the central portion of the front member 24 of the top frame. A draft rod 44 is hooked at its rear end and adapted to engage by downward movement in the eye of the member 43, and also is laterally hooked at its opposite end and adapted to be engaged by lateral movement in an eye 45 on the tongue or handle 21. Thus the draft rod 100 105 is pivoted on a horizontal axis relative to the handle and on a vertical axis relative to the top frame. When the draft rod 44 is engaged with the eye 43 and eye 45 the handle 21 may be employed as a lever to pull 110 the top frame forward on the bottom frame and elevate said top frame relative to the

bottom frame through the inclined planes and rollers above described; or to move the top frame rearwardly and lower the same relative to the bottom frame.

- 5 A cross-bar 46 is mounted across the lower frame at the rear of the cross-bar 14 and a lug 47 is fixed to and projects upwardly from said bar 46. A bracket 48 is fixed to and projects downwardly from the cross-bars 28, 29 of the upper frame and a latching member 49 is pivoted on and depends from said bracket and is formed with a notch in its lower face adapted to engage at times with the lug 47. A retractile coil 15 spring 50 is fixed at one end to the rear end of the bracket 48 and at the other end to the rear end of the latching member 49, and tends to hold the forward or notched end of the latching member down to establish and 20 maintain engagement with the lug 47. The latching member 49 is bent upwardly at its rear end at the rear of the cross-bar 28. A tripping rod 51 is slidably mounted through the front member 24 of the top frame and through the cross-bar 28 thereof and impinges at its rear end the upturned rear portion of the latching member 49. The forward end of the tripping rod 51 rests on the eye member 43 and is formed with 25 an eye 52 adapted to be engaged by the hooked rear end of the draft rod 44 simultaneously with the engagement thereof with the eye 43. A stop 53 is fixed to the tripping rod 51 at the rear of and is adapted 30 to contact with the cross-bar 28 and limit forward movement of said tripping rod, when the rod 44 is disengaged from the eye 52 thereof and the truck is being moved around.
- 35 40 In practical use the truck is wheeled in lowered position to and beneath a platform such as 54 (see Fig. 3) containing a load to be moved. The platforms 54 may be of any desired construction except that they must be open at the end to admit the truck beneath them. They may be used for any desired purpose, but I have designed this improvement especially for use in printing establishments where paper stock is stored 45 on such platforms in the stock room, and the truck employed to raise and convey the loaded platforms to desired points of use. When the truck is in position the draft rod. 50 44 is engaged in the eye 52 of the tripping 45 rod and in the eye 43 of the top frame, thus connecting it to the tongue 21, and the free end of said tongue is moved forwardly on its pivot, thus applying forward draft to the top frame, and causing the planes 42 to rise 55 60 on the respective rollers and elevate the top frame, and with it the loaded platform. The planes 42 preferably are formed with horizontal planes at their rear ends adapted to rest on the rollers in elevated position.
- 65 When the top frame has reached its elevated

position, the latching member 49, assisted by the spring 50, engages the lug 47 and holds said top frame and the load in such position until released. The draft rod 44 may then be released from the eyes 43 and 70 52 and the tongue or handle 21 be employed to move and guide the loaded truck to the desired place of deposit. When it is desired to lower the platform the handle or tongue 21 is raised to approximately perpendicular position and the draft rod again engaged in the eyes 52 and 43. The eye 43 is formed somewhat longer than the eye 52, so that in rearward movement of the draft rod 44 there is a slight play in the eye 43 and 75 80 pressure is first applied to the eye 52. This pressure causes a slight rearward movement of the tripping rod 51, which contacts with the upturned rear end of the latching member 49, moves said latching member on its pivot, and releases engagement thereof with the lug 47, against the tension of the spring 50. The top frame is thus released from the bottom frame and further rearward movement of the tongue or handle 21 applies a 85 90 pressure through the eye 43 to said top frame and causes it to move rearwardly and downwardly toward the bottom frame, thus lowering the loaded platform to the floor and permitting withdrawal of the truck. 95

Stops 55 are fixed to side members of the top frame and are adapted to engage at times the cross-bar 46 of the bottom frame and limit forward movement of said top frame. Stops 56 are fixed to the side members of the top frame and are adapted to engage at times the cross-bar 15 of the lower frame and limit rearward movement of said top frame. 100

The adaptation of inclined planes working 105 on fixed rollers to the elevation of the top truck frame renders the device exceedingly efficient and easy to operate, as a load of a ton or more may readily be lifted by one man without undue effort. 110

I claim as my invention—

1. A lifting truck, comprising a bottom frame provided with supporting wheels, a top frame thereon, a draft handle on said bottom frame, means connected with said draft handle for moving the top frame forwardly relative to the bottom frame, means for elevating the top frame relative to the bottom frame in such forward movement a latching member pivoted on the top frame 115 and adapted to engage in the bottom frame, and a tripping rod slidably mounted in said top frame and pivotally connected to and adapted for actuation by said draft handle, said tripping rod adapted to engage 120 and release said latching member. 125

2. A lifting truck, comprising a bottom frame provided with supporting wheels, a top frame thereon, a draft handle on said bottom frame, a draft rod on said handle 130

engaging an eye on said top frame, a latching member pivoted on said top frame and adapted to engage the bottom frame, a spring acting to hold said latching member in operative position, and a tripping rod formed with an eye at its forward end engaged by said draft rod and adapted to engage and release said latching member, the eye of the top frame being elongated relative to the eye of said tripping rod.

3. A lifting truck, comprising a bottom frame, supporting wheels thereon, a handle pivoted on a horizontal axis on said bottom frame, rollers mounted for rotation on said bottom frame, a top frame formed with inclined planes adapted to contact with said rollers in forward movement of the top frame, a draft rod pivotally and detachably connecting said top frame and the handle, a latching lug on the bottom frame, a latching member pivoted on the top frame and notched for engagement with said lug, and tripping means acting between said draft rod and the latching member.

4. A lifting truck, comprising a bottom frame, supporting wheels thereon, a handle pivoted on said bottom frame, rollers mounted for rotation on said bottom frame, a top frame formed with inclined planes adapted to contact with said rollers in forward movement of the top frame, an eye on the front of the top frame, an eye on said handle, a draft rod detachably engaging said eyes, a latching lug on the bottom frame, a latch-

ing member pivoted on the top frame and notched for engagement with said lug, said latching member formed with an upturned rear end portion, and a tripping rod slidably mounted and engaged at its forward end by said draft rod, said tripping rod impinging at its rear end the upturned portion of said latching member.

5. A lifting truck, comprising a bottom frame, supporting wheels thereon, a handle pivoted on said bottom frame, rollers mounted for rotation on said bottom frame, a top frame formed with inclined planes adapted to contact with said rollers in forward movement of the top frame, an eye on the front of the top frame, an eye on said handle, a draft rod pivotally and detachably connecting said eyes, a latching lug on the bottom frame, a latching member pivoted on the top frame and notched to engage said latching lug, said latching member formed with an upturned rear end portion, and a tripping rod formed with an eye at its forward end engaged by said draft rod and engaging at its rear end the upturned end of said latching member, the eye of the top frame being slightly longer than the eye of said tripping rod.

Signed by me at Kansas City, Missouri, this 29 day of May, 1913.
